[57] CLAIM

The ornamental design for the cylindrical lens cleaner, as shown and described.

DESCRIPTION

FIG. 1 is an isometric view of the cylindrical lens cleaner with a cap therefor shown in broken lines for illustrative purposes only and forms no part of the claimed design;

FIG. 2 is an end view of one end thereof;

FIG. 3 is an end view of an end opposite the end of FIG. 2;

FIG. 4 is a front elevation thereof;

FIG. 5 is side elevation thereof, the other side being a mirror image; and,

FIG. 6 is a rear elevation thereof.

FIG. 6

FIG. 5

FIG. 4

FIG. 2

FIG. 1

FIG. 3
